HAND OPERATED AEROSOL SPRAY DEVICE

Harold D. North, Jr., Shaker Heights, Ohio, assignor to Engine Parts Manufacturing Co., Cleveland, Ohio, a corporation

Application August 29, 1947, Serial No. 771,175

3 Claims. (Cl. 239—302)

My invention relates to a hand operated spray and relates more particularly to a hand operated spray of the hand grenade or bomb type adapted to propel a fine spray of insecticide, perfumes, hormones, bactericides, therapeutics etc. under pressure, by action of a liquified gas, such as "Freon," carbon dioxide, propane, methyl chloride, nitrogen, or the like, contained in a closed chamber, the chemical substances being dissolved in such liquified gas and being freed of the solvent upon exposure to the air and change of solvent from liquid to vapor state. The great expansion of the solvent upon its change of state is employed in such related uses to propel the chemical.

It is an object of my invention to release the chemical contents of such liquified gas chamber in the form of a predetermined spray, the liquified gas which carries the admixture evaporating upon contact with the atmosphere and acting primarily as a propelling or dispersing medium or vehicle for such chemical substance.

It is the further object of my invention to control the spray according to a predetermined velocity volume and spray pattern by means provided in said container.

Another object of my invention is to provide means in connection with the dispensing container described herein which will remove or filter particles therefrom.

Another object of my invention is to provide means for accentuating the spray characteristics of an "Aerosol" bomb of the type described.

A still further object of my invention is to provide a container and dispenser for such liquified gas solvents.

A further object of my invention is to provide a dispensing container of the type described which will be inexpensive to manufacture being composed of relatively few parts and highly efficient in use.

A further object of my invention is to so construct the dispensing container of my invention, to enable the same to be transported safely and to be perfectly sealed against accidental explosion.

Other objects of my invention will become more readily apparent from a review of the following description in which description reference will be had to the accompanying drawings, in which drawings:

Figure 1 is a vertical plan view, of the dispensing container of my invention, certain portions being cut away to illustrate more graphically the assembled relationship of the parts of my invention.

Figure 2 is a detailed view of a feeding element associated with the container of my invention, the lower part thereof being shown in side elevation.

Figure 3 is a detailed view of a valve adapted to be associated with the liquified gas chamber of my invention.

Figure 4 is a front plan view taken from line 4—4 of Figure 1.

Figure 5 is a perspective view of a spring member associated with the thumb operated lever illustrated in Figures 1—4.

2

Figure 6 is a plan view of the cap and associated valve used in the embodiment of Figure 1.

Referring now to the drawings in all of which like parts are designated by like reference characteristics, at 10, I 5 show a ball-shaped grenade type container, formed of two hemispherical metal shells, 20 and 21, the upper shell, 20, having a peripheral band, 11, adapted to be telescoped over a peripheral portion of the lower shell and to be welded or brazed thereto. The upper hemispherical shell 10 portion, 20, is formed with a central aperture, 22, through which a cylindrical tube, 23, is adapted to be projected, the upper portion of the tube or stem insert, 23, being screw-threaded as shown at 12. The stem insert, 23, is further formed with a stepped relatively smaller diameter portion, 13, and an inlet end, 14, which elongated portion is of relatively lesser diameter than the adjoining portion, 13, and threaded relatively wider portion, 12. The elongated portion of the stem, 14, may be formed either integrally with the tube, 23, or separately formed and secured thereto as by welding, or the like. The screw-threaded portion, 12, of the tube, 23, is adapted to be projected through the aperture, 22, and to be maintained in position by a nut, 15, which is screw-threaded thereon before welding the two shells together. An adjusting or positioning ring, 17, is screw-threaded over the portion, 12, of the tube extending outwardly of the container, 10.

A thumb operated lever 18 is secured to the tube 23, as best illustrated in Figures 1 and 4. The said lever is provided with a thumb operated portion, 19, secured by means of a pin, 24, to a ring member 25 telescoped over the upper end of the tube 23 above the positioning ring 17, said ring member 25 having a pair of apertured upstanding members 26 and 26 through which the pin, 24 is projected. A flat spring member 27 having a pair 30 of eye members 28 and 28 journaled over the pin 24 is provided with a pair of spaced leg members 29 and 29 and a crimped portion 30 provided for a purpose later herein described. The leg members and crimped portion 30 are maintained in contiguous relation to the underside of the thumb portion 19 and a portion of the ring member 25 is adapted to be encircled by the adjusting or positioning ring 17 and to be retained in a predetermined position by means thereof. A small discharge orifice 31 is provided in a portion of the upper screw-threaded portion of the tube 23 and the adjusting ring 17 is turned sufficiently to enable the orifice 31 to be positioned between the upstanding members 26 and 26 wherefore the spray material propelled through the orifice will be unobstructed.

50 A small valve, 32, similar to that in type of a tire valve, is screw-threaded by means of the screw-threaded portion 33 thereof within the tube 23, a spring operated stem 34 projecting upwardly of the threaded connection and adapted to be pressed downwardly by the crimped portion 30 of the spring 27 by means of pressure exerted thereon by the thumb operated lever 19. A perforated cap sealing member 35 is securely threaded over the upper portion 12 of the tube 23 and the ring member 25 and the stem 34 projects upwardly through the perforation 36 in the cap member 35.

Filtering material M, such as felt or like material or other porous element, is disposed within the narrow tube 23 and filters the liquid gas and the admixture carried thereby in solution form in the container, as well as acting as a capillary feeding element. The tube 14 carrying the filtering material extends well into the container and into the solution extending to a point spaced from but adjacent to the bottom of such container (see Figure 1).

The filtering material also extends upwardly into the portion 13 of the tube. A portion of filtering material M is preferably first driven into the tube portion 14 until that portion of the tube shown at "s" is tightly packed by

means of a rod driven into the tube to compress the material therein. The tube 14 is then preferably "kinked" or distorted, as shown in Fig. 2, a certain predetermined amount, to retain the initial compression, achieved by packing the wad to a predetermined density and compression. A second length of filter material M, is then driven into the remainder of the portion of the tube 14, which acts as the capillary feeding element or wick as hereinbefore described. The filter provided is highly efficient in protecting the valve mechanism 32 and preventing such valve mechanism and discharge orifice 31 from clogging.

It should be noted moreover that the degree of compression of the filter material is predetermined according to the density thereof and according to the predetermined rate of flow desired, said rate of flow referring to the rate of flow of the solution from the container through the discharge tube and orifice. The said predetermined rate of flow is achieved by the initial and retained compression of the first filter material which causes it to act as a "throttle" on the flow of the solution prior to its passage through the discharge orifice, providing the desired control of the spray produced as a result of the expansion of the liquifier gas, when the valve stem 34 is depressed permitting the flow of the same through the orifice 31 into the atmosphere.

The lower hemispherical shell is preferably apertured as shown at 41 and brazed or welded or soldered at 42.

It will be understood that certain changes may be made in the construction of my invention, as described herein in connection with the preferred embodiment of my invention, without departing from my invention and the scope of the appended claims.

I claim:

1. A dispensing device comprising in combination, a container for low pressure liquified gas solutions, said container being provided with a discharge conduit having a portion thereof projecting outside said container, a discharge orifice disposed in that portion of said discharge conduit disposed outside of said container, said discharge conduit having a portion thereof disposed within said container, valve means disposed within the said conduit, compressed filtering material disposed within that portion of the said conduit extending within the body portion and adapted to restrict the rate of flow of the said liquid through the said material at a pre-determined rate, said conduit being distorted at one point to maintain said material under compression, a ring member telescoped over said conduit outside said container, a lever pivoted upon said ring member, said lever adapted to operate

said valve means to release the liquid under pressure through said discharge orifice.

2. A dispensing device comprising in combination, a container for low pressure liquified gas solutions, said container being provided with a central aperture, a cylindrical tube extending into said container, said tube being provided with an upper threaded portion having a small orifice therein, a stepped relatively small diameter portion, and an elongated inlet end, the threaded portion of said tube being projected through said container aperture, securing means being screw threaded thereon to retain said tube within the container, an adjusting ring telescoped over a portion of said screw threaded tube and upon said securing means, a thumb operable lever secured to said adjusting ring, valve means telescoped within the upper portion of said tube, said lever adapted to operate said valve means, compressed filtering material injected within the upper end of said tube to a point adjacent the valve means, a distortion in the tube for maintaining said material to a predetermined degree of compression, additional filtering material under less compression within the remaining length of the tube and extending to a point adjacent to but spaced from the wall of the container, said additional material acting as a wick.
3. A dispensing device for low pressure liquified gas solutions, comprising a container for said gas solutions, valve means mounted to said container having means exterior of said container to actuate said valve, a fluid conducting conduit contained within said container, said conduit comprising a tubular member having one end thereof connected to said valve means, filtering material under compression disposed within said tubular member adjacent said valve means, said tubular member distorted at a medial portion thereof to maintain said filtering material under compression, and additional filtering material disposed within said tubular member adjacent the end thereof opposite said valve means.
